UNITED STATES PATENT OFFICE

EUGENE LOOSLI, OF ILION, NEW YORK

ELECTRIC PLUG

Application filed March 2, 1932. Serial No. 596,387.

This invention relates to an electric plug or connection, the general object of the invention being to provide means whereby one part of the connection can have rotary movement in relation to the other part so that the conductors will not be twisted when they are given a rotary movement.

This invention also consists in certain other features of construction and in the combination and arrangement of the several parts to be hereinafter fully described, illustrated in the accompanying drawing and specifically pointed out in the claims appended.

15 In describing the invention in detail, reference will be had to the accompanying drawing wherein like characters denote like or corresponding parts throughout the several views, and in which:—

20 Figure 1 is a sectional view thru the invention.

Fig. 2 is a sectional view through the shell before being bent and before receiving the insulated covering.

25 Fig. 3 is a section on line 3—3 of Fig. 1.

Fig. 4 is a similar view but showing a modification.

In the drawing, the letter A indicates the stationary part of the device which is formed 30 of a metal shell 1 having its bottom formed with a tubular part 2 exteriorly threaded to fit in a threaded socket and this tubular part contains a block 3 of non-conducting material through the center of which passes a metal 35 tube 4, the upper end of which is slightly contracted to form a seat for a ball 5 which is normally held upon the seat by the spring 6 in the tube, and the spring is held in place by a screw 7, screwed into the lower end of 40 the tube. The upper part of the shell 1 is bent inwardly to form a flange which acts to hold a raceway 8 in the shell, the major part of the shell being covered by insulating material 9. A number of balls 10 are carried by an annular spacer member or ball cage 45 11, these balls partly fitting in the groove of the raceway 8 and these balls also fit in an exterior groove formed in a central tubular part 12, the outer end of which flares outwardly as shown in Fig. 1. This tubular

part is internally threaded to receive the usual plug 13 and the flaring part of the tubular member 12 is covered with insulating material as shown at 14.

Thus it will be seen that the plug 13 can be 55 screwed into the member 12 and that said member 12 is rotatably supported in the member A through means of the balls 10 so that the plug 13 and the part 12 rotate in the member A thereby preventing twisting of 60 the wires or conductors connecting the plug 13 when the same are turned or rotated in any manner, which rotary movement to the parts will not interrupt the flow of current, it of course being understood that the center contact of the plug 13 engages the ball 5 as shown in Fig. 1, while the plug is electrically connected to the part 2 through the member 12, balls 10, the raceway 8, and the shell 1, to which the tubular part 2 is connected. 70

When the device is to be used as a signal device, or instrument, where it is desired to alternately make and break the circuit during the rotation of the member connected with the plug 13, strips 15 of non-conducting material can be embedded in the raceway 8' so that the balls 10' will contact these strips during the rotation of the parts 12' and when this occurs, the current is broken but as soon as the balls pass off the strips onto the metal of the parts or raceway 8' the circuit will be made again and thus the circuit will be alternately opened and closed. 75

It is thought from the foregoing description that the advantages and novel features of the invention will be readily apparent. 80

It is to be understood that changes may be made in the construction and in the combination and arrangement of these several parts provided that such changes fall within the scope of the appended claims. 85

Having thus described my invention, what I claim as new is:—

1. A device of the class described comprising a stationary part having a raceway therein, a tubular part connected with the first-mentioned part and electrically connected with the raceway, a block of non-conducting material placed in the tubular part and con- 90

taining a contact, a plug receiving member rotatably arranged in the first part, balls placed between the raceway and the plug receiving member, a plug in said member and 5 removably arranged therein and having its center contact engaging the first-mentioned contact, and spaced strips of insulating material forming portions of the raceway for interrupting the circuit when the balls engage the same.

2. A device of the class described comprising a metal shell having a reduced tubular portion extending from its bottom for fitting in a socket, a member of non-conducting 15 material located in said tubular portion, a contact carried by said member, a raceway in the shell, the upper edge of the shell being

bent over upon the raceway to hold the same in place, said bent over portion forming an opening in the top of the shell, a plug carrying member extending into the shell through said opening and having an exterior groove 70 therein, balls located between the raceway and the lower part of said plug carrying member and having portions fitting in the groove in said plug carrying member, a plug threaded in said member and having its center 75 contact engaging the first-mentioned contact, said plug carrying member having its upper end flaring outwardly to provide a finger engaging part and a cover of non-conducting 80 material for said part.

In testimony whereof I affix my signature.
EUGENE LOOSLI.
